UNITED STATES PATENT OFFICE

91,807

DESIGN FOR A SMOKING STAND

George Engelson, Newark, N. J.

Application March 2, 1933, Serial No. 47,389

Term of patent 3½ years

To all whom it may concern:

Be it known that I, GEORGE ENGELSON, a citizen of the United States, residing at Newark, in the county of Essex and State of New Jersey, have invented a new, original, and ornamental Design for Smoking Stands, of which the following is a specification, reference being had to the accompanying drawing, forming part thereof.

In the drawing:

Figure 1 is a perspective elevation of a smoking stand embodying the present invention;

Figure 2 is a plan view of the smoking stand of Figure 1; and

Figure 3 is a rear elevation of the smoking stand of Figure 1.

I claim:

The ornamental design for a smoking stand, as shown.

GEORGE ENGELSON.
